United States Patent Office.

ADAM ROSENBERGER, OF BRANDONVILLE, WEST VIRGINIA.

Letters Patent No. 63,752, dated April 9, 1867

IMPROVEMENT IN HAND-LOOMS.

The Schedule referred to in these Letters Patent and making part of the same.

TO ALL WHOM IT MAY CONCERN:

Be it known that I, ADAM ROSENBERGER, of Brandonville, in the county of Preston, and State of West Virginia, have invented a new and improved Hand-Loom; and I do hereby declare that the following is a full, clear, and exact description thereof, reference being had to the accompanying drawings, forming part of this specification.

This invention embraces novel appliances for effecting the shifting of the harness, and the specific adjustment of the same.

To enable others skilled in the art to make and use my invention, I will proceed to describe its construction and operation.

Figure 1 is a longitudinal vertical sectional elevation of my improved hand-loom from the line $x\ x$, fig. 2.
Figure 2 is a top plan view of the same.

Letters of like name and kind refer to like parts in each of the figures.

A represents the frame of my improved loom, made of wood, and of any desired dimensions, constructed of four pieces of timber, framed diagonally across each other, and connected and secured together by a cross-centre-plank or suitable piece of timber, B. At the crossing, and in the centre of each side of the frame A, are erected two posts C C, the tops of which are connected or secured together by means of a cross-timber, D. Upon the centre plank or timber B is a short vertical post, E, located in the centre of the said plank. To this post E are attached four pieces, F F F F, that are secured by screws, or other equivalent means, to the said post E. To these are connected, by a joint, treadles G G G G, at the ends of which are hooks H H, that run back a short distance parallel with the treadles G G, &c. To these hooks the harness-cords $\alpha\alpha$ are attached, as shown in the drawing. (It will here be observed that the machine is geared for weaving flannels, linsey, linen, and all kinds of plain fabrics.) The harness-frames I are suspended by cords $e\ e$, from the pulley J, that runs in an adjustable pendant K, which is adjusted by the screw L, the said pendant being connected to the top cross-piece D. M M are cords that are attached to each end of the harness-frames I I, and then connected with the lower ends of pins N N, located on the top cross-piece D. These pins are surrounded and sustained by spiral springs, in order to bring the harness-frames back to their original positions after they have been lowered. Upon the end of the treadles G G G G are curved projections $i\ i\ i$, that extend forward and engage the staples O O O O, located at equal distances in the shaft or roller P, that has bearings and works in the triangular frame Q. This triangular frame Q is attached to the under side of the lathe R, and its lower portion turns on a rod, having its bearing in the ends of bars S S, that are also connected by a pivot bolt to the post E. In this manner the frame Q works upon pivots on the under side of the lathe R and upon the ends of the bars S, so that at every alternate motion of the lathe the roller P in the lower end of the frame is depressed, and one of the staples O, in the roller P, engages one of the curved projections i , and brings down one of the harness-frames until the staple thus engaged becomes released, when, by the action of the spring surrounding the pins N, that harness is again raised to its original position, when the other staple becomes engaged, and so on, at each alternate motion of the lathe. T is the warp-beam, located and having bearings in the rear end of the frame A. U is a pivoted lever, in the lower end of which is a roller. This lever U is pivoted to the side of the frame A at n . V is the cloth-beam that has bearings and is located in the frame A, near the front end thereof. Y is a cord or band that extends over and works around pulleys at each end of the warp-beam T and cloth-beam V, so that they work simultaneously. When the cloth is taken up around the beam V, the warp is also let off in a corresponding proportion. The pulley in the end of the lever U is used as a tightener of the cord or band Y, and may be secured in any desired position by means of the cord W around the ratchet-pulley w , which is held in position by the pawl m . b is the shuttle, partially shown in dotted lines, that is thrown back and forth by the action of a pivoted cam-lever, d, located in the centre of the lathe R. The said cam-lever is acted upon by another lever, f, pivoted at its end to the breast-beam. To the cam-lever are attached two cords c c, extending in opposite directions to each other, and attached to blocks y y, located in each end of the lathe R, so that by the sudden action of the pivoted cam-lever d, caused by the action of the lever f, upon the blocks y y, the shuttle is forced from end to end of the lathe at every motion. It will be seen that the lathe R is pivoted at the lower end to the frame A, instead of being overhung. Immediately behind the roller P is a beard, g, pivoted at the upper end to the triangular frame Q, in which is a spring, h, that acts against the

board *g*, and which keeps the roller *P* in proper position. Underneath the centre plank *B* is a spiral spring, *l*, that connects by a cord to the cap-piece *p*, that is located over the post *E* and pieces *F*, to form a bearing for the tongues as they are operated up and down.

The operation is simple and perfect. After the warp or piece is in the loom, the operator simply works the lathe back and forth, by the action of which, through the medium of the triangular frame *Q* and roller *P*, the harness-frames are worked or operated in a proper manner. The shuttle is also worked by the action of the lathe through the medium of the cam-lever *d* and pivoted lever *f*. When the levers stand in the position as shown in fig. 2, by the backward movement of the lathe, the lever *f* throws the cam-lever *d* around in such a manner as to throw the shuttle in the direction of the arrow, when by the forward movement of the lathe the lever *f* passes the end of the cam-lever *d* upon the other side, when, again, by the backward movement of the lathe, the shuttle is thrown back, and so at each alternate motion of the lathe.

Having thus described my invention, what I claim as new, and desire to secure by Letters Patent, is—

1. The combination with the roller *P*, staples *O*, and pivoted frame *Q*, of the hooks *H* *i*, treadles *G*, attaching pieces *F*, and levers *S* *S*, all constructed and arranged in the manner described, and employed to effect the shifting of the harness as set forth.
2. In combination with the above, I claim pendant *K*, thumb-screw *L*, pulley *J*, and cords *e*, arranged as described, and employed for adjusting the harness as specified.

ADAM ROSENBERGER.
